UNITED STATES PATENT OFFICE.

GEORGE SELDEN WATTS, OF MARIETTA, GEORGIA, ASSIGNEE TO UNDERWOOD TYPE-WRITER COMPANY, OF NEW YORK, N. Y., A CORPORATION OF NEW JERSEY.

TYPE-WRITER ATTACHMENT.

1,143,871.

Specification of Letters Patent. Patented June 22, 1915.

Application filed April 21, 1909. Serial No. 491,392.

To all whom it may concern:

Be it known that I, GEORGE SELDEN WATTS, a citizen of the United States, residing at Marietta, in the county of Cobb and State of Georgia, have invented new and useful Type-Writer Attachments, of which the following is a specification.

This invention has reference to improvements in typewriter attachments and relates more particularly to an attachment for the ribbon carrier whereby the paper being written upon is maintained in close relation to the platen of the typewriting machine in such manner that the typewriting may be continued to the lowest margin of the paper, the paper being held in proper relation to the platen even beyond the lowermost printing zone.

The invention will be best understood from a consideration of the following detail description taken in connection with the accompanying drawings forming a part of this specification, in which drawings,

Figure 1 is a perspective view of the ribbon carrier of a known type of typewriter with the invention applied thereto. Fig. 2 is a perspective view of another form of the invention. Fig. 3 shows a portion of an Underwood typewriter in section, with my improvements applied thereto.

Referring to the drawings there is shown a ribbon carrier 1 of the vibratory type such as is used upon the typewriting machine known commercially as the Underwood typewriter, but so far as the invention is concerned this ribbon carrier is to be taken as typical only and not as confining the use of the invention to this particular make of typewriter.

The ribbon holder is shown as provided with a central opening 2 which, in the normal operation of the machine, is traversed by the ribbon. It is through the opening 2 that the type engage the ribbon and carry the same to the paper to form the impression against the traveling platen, which latter is shown in dotted lines at 3 in Fig. 1, and in Fig. 3 in full lines in its normal position, and in dotted lines in its shifted position.

In accordance with the present invention the ribbon carrier 1 on each side of the opening 2 is provided with wings 4 and 5, one wing extending in one direction along the

length of the platen from the opening 2 and the other wing extending in the opposite direction. These wings are in the form of plates fast on one end to arms 6 flanking the opening 2 and at the lower end joined to the ribbon carrier 1. The arms 6 are made in one piece with the wings 4 and 5 and said parts 4, 5 and 6 may be made of one stamping of sheet metal of elastic nature such as spring brass, and the space between the adjacent ends of the wings 4 and 5 is sufficient to prevent any interference with the ribbon when struck by the type.

The outer ends of the wings 4 and 5 are outward as indicated at 7 and the upper edge of each wing 4 and 5 is provided with spacing or indicating marks 8 of any appropriate character and extending upward from these edges the wings have pointed projections 9.

The ribbon carrier 1 is usually mounted on a lever 15, operated at every type stroke by a universal bar 16. The platen 3 is mounted on a carriage 17 traveling on a front rail 18 and a rear rail (not shown). The carrier 1 slides up and down on a fixed guide 19.

Let it be assumed that with a machine of the character to which this invention relates, but without the invention attached, the typewriting operation proceeds until the lower edge of the paper is being approached. On the Underwood type of machine there is provided what is known as a "wing" scale plate and when the shift or capital key is depressed and the platen and paper is lifted, the spring of the paper at the lower edge of the sheet carries this lower edge out away from the platen so that when the key is released and the platen is lowered the lower edge of the paper catches on the wing scale plates and so displaces the sheet, and no further writing can be done on the unfinished line. This trouble is entirely avoided by the use of the structure of the present invention and when the structure of the present invention is attached to the typewriting machine the wing scales commonly found on machines of the type to which this invention relates need not be used, and as the cost of these wing scales is considerably more than the cost of the attachment forming the subject matter of the present invention, the use of the present invention on the machine

not only avoids the annoying condition above mentioned but may actually reduce the cost of manufacture so far as this particular part of the machine is concerned.

5 The graduations 8 on the upper straight edges of the wings 4, 5 enable them to serve the same purpose as the "wing" scale plates above referred to, viz., to position the paper on the platen (the upper edges of the 10 "wing" scale plates always registering with the printing point or line on the platen, and the upper edges of wings 4, 5 doing the same when in normal positions, *i. e.*, when the ribbon vibrator is down to disclose or 15 uncover the line of writing).

When the invention is in proper relation to the platen then the wings bear with very slight elastic pressure on the platen thus retaining the paper in proper relation thereto 20 even though the lower edge of the paper be held only by the fingers or projections 9, these projections normally covering the printing line on the platen and serving as extended fingers for holding the paper even 25 after it leaves the upper margin of the wings 4 and 5 and therefore the lower edge of the paper cannot spring out because of its natural elasticity, when, during the operation of writing the lowermost line, the shift 30 or capital key is depressed and the platen and paper is lifted so that the lower edge of the paper is above the wings 4 and 5. The fingers or projections 9, under these conditions, exert a horizontal tensional effect, that 35 is they keep the papers under tension and flat against the platen despite the tendency of the paper to spring out and away from the platen because of its inherent elasticity. Under these conditions when the key is released and the platen is lowered the paper 40 will keep or again return to its proper position with relation to these wings. It will be understood that in said Underwood machine the ribbon vibrator 1 rises and falls with the 45 platen 3 when the latter is shifted up and down.

The out-turned ends 7 of the wings 4 and 5 not only prevent interference with the paper upon which the typewriting is produced but also serve to guide the wings over and on top of the ordinary compressor arms or springs which are present in the typewriter for holding the paper firmly to the platen at the extremity of the writing zone.

55 In Fig. 2 the wings 4 and 5 are the same as shown in Fig. 1 and also the arms 6 are like those in Fig. 1, but these arms are continued and returned on themselves in the form of other arms 10 similar to the arms 60 6 and both the arms 6 and 10 are joined together and to each other by a yoke 11 which may be in one piece with the said arms. The free ends of the arms 10 are formed with side extensions 12 having the outer ends 65 curved to form elongated sockets 13 properly

shaped to slip over the vertical post 14 on either side of and forming a part of the ribbon carrier of the ordinary Underwood machine, thus holding the attachment in place without making it a permanent part of the 70 structure as in the form shown in Fig. 1. The ribbon maintains its normal position on the ribbon carrier while the attachment occupies the space between the normal ribbon carrier and the platen, both arms 6 and 10 75 of the structure shown in Fig. 2 occupying the position of the arm 6 of the structure shown in Fig. 1.

What is claimed is:—

1. In a typewriting machine, the combination with a ribbon carrier, a platen, of elastic wings adapted for light pressure against the platen fast on said ribbon carrier, each of said wings being provided on its upper edge with projecting fingers extending on 80 each side the printing point over the printing line, in the direction of travel of the paper with the platen when the latter is moved about its longitudinal axis to cause 85 line spacing of the paper, in order to keep 90 said paper from springing from said platen.

2. In a typewriter, the combination with a ribbon carrier of a typewriter, of wings adapted for light pressure against the platen on either side of the type striking zone, 95 each wing having on its upper edge spaced fingers extending over a tensionally operative horizontal range, each side the printing point, said fingers projecting from said edge to keep paper from springing from said 100 platen, and index marking between the fingers.

3. In a typewriting machine, the combination with a ribbon carrier of a typewriter machine, said ribbon carrier being provided 105 with a space for the passage of the type, a platen, of wings adapted for light pressure against the platen mounted on said carrier and having a normal tendency toward the platen to hold paper against said platen, 110 said wings each being provided with upwardly projecting fingers extending over a tensionally operative horizontal range each side the printing point, one of said fingers being adjacent to the typewriting zone. 115

4. In a typewriting machine, the combination with a ribbon carrier of the typewriter, a platen, of wings adapted for light pressure against the platen on either side of the striking zone of the type, said wings being 120 each elastically mounted on the ribbon carrier and spaced apart at contiguous ends and each provided on the other end with index marking and spaced fingers projecting in the direction of travel of the paper being 125 printed, said fingers extending over a tensionally operative horizontal range on each side the printing point and being arranged to hold the paper against the platen of the typewriter. 130

5. In a typewriting machine, the combination of a platen, of a ribbon carrier provided with opposite wings adapted for light pressure against the platen, each of said wings being in the form of a plate fast on one end to one of a pair of arms flanking the opening in the ribbon carrier, joined to the ribbon carrier, and arranged to keep work from springing from the platen, said 10 arms extending from a tensionally operative horizontal range each side the printing point.

6. In a typewriting machine, the combination with a platen, of a ribbon carrier 15 having an opening therein, opposite wings adapted for light pressure against the platen extending each side of the opening, a pair of arms flanking the opening in the ribbon carrier, each of said wings being fast to one 20 of said arms, each of said wings being joined at its lower end also to the ribbon carrier, said arms being made in one piece with said wings, and pointed projections extending upward from the wings across the line of 25 print.

7. In a typewriting machine, the combination with a platen, of a ribbon carrier provided with opposite wings adapted for light pressure against the platen, each of 30 said wings being in the form of a plate fast on one end to one of a pair of arms arranged to hold work close to the platen, said arms extending over an operative horizontal range each side of the printing point and 35 flanking the opening in the ribbon carrier and at the lower end being joined to the ribbon carrier; the plates between the contiguous ends of the wings being sufficient to prevent any interference with the ribbon 40 when struck with the type.

8. In a typewriting machine, the combination with a platen, of a ribbon carrier provided with opposite wings each in the form of a plate fast on one end to one of a 45 pair of arms flanking the opening in the ribbon carrier, and at the lower end joined to the ribbon carrier; the space between the contiguous end of the wings being sufficient to prevent any interference with 50 the ribbon when struck by the type; the outer ends of the wings being out-turned and having scale marks thereon, and pointed projections forming fingers to hold work against the platen extending up from the 55 wings.

9. In a typewriting machine, the combination with a platen, of a ribbon carrier provided with opposite wings each in the form of a plate fast on one end to one of a 60 pair of arms flanking the opening in the ribbon carrier, and at the lower end joined to the ribbon carrier; the space between the contiguous end of the wings being sufficient to prevent any interference with the ribbon 65 when struck by the types; the outer ends of

the wings being out-turned and having scale marks thereon, and pointed projections extending up from the wings; the arms formed with side extensions having outer ends bent to form elongated sockets properly shaped 70 to slip over the vertical posts on either side of the ribbon carrier.

10. In a typewriting machine, the combination with a traveling platen and a ribbon vibrator having an opening through which 75 the types strike, of scales upon each side of the said opening, adapted for light pressure against the platen, and extending along said platen, substantially as described.

11. In a typewriting machine, the combination with a platen and a ribbon-vibrator having an opening through which the types strike, of a paper-guiding finger or projection secured upon said ribbon-vibrator and projecting therefrom to cover the printing 80 line, and serving as a guide for the lower edge of the paper as it turns or feeds around said platen.

12. In a typewriting machine, the combination with a traveling platen and a vibrating ribbon carrier, of a scale plate mounted on said carrier so that the platen travels with relation to the same, and a paper guide projecting up from said scale plate to cover the printing line. 90

13. In a typewriting machine, the combination with a traveling platen and a vibrating ribbon carrier, of a pair of paper-guiding scale plates on said carrier, one upon each side of the printing point, each having 100 a paper-guiding point projecting up to cover the printing line.

14. In a typewriting machine, the combination with a traveling platen and a vibrating ribbon carrier, of a pair of paper-guiding scale plates on said carrier, one upon each side at the printing point, each having 105 at suitable interval points projecting up to cover the printing line.

15. In a typewriting machine, the combination with a platen and a ribbon vibrator having an opening through which the types strike, of a pair of paper-guiding scale plates secured to said ribbon vibrator and having paper-guiding points projecting up to cover 110 the printing line.

16. The combination with a shiftable platen and a ribbon vibrator shifting with the platen, of resilient wings on said vibrator arranged to hold against said platen 115 a work sheet.

17. The combination with a shiftable platen and a ribbon vibrator shifting with the platen, of resilient wings on said vibrator arranged to hold against said platen a work sheet, and a finger on each wing extending 125 across the printing line.

18. The combination with a shiftable platen and a ribbon vibrator shifting with the platen, of a finger on said vibrator ar- 130

- 4
- ranged to extend across the printing line to hold the paper in position whenever the edge of the paper approaches the printing line.
19. The combination with a shiftable platen and a vibrating ribbon carrier, of a paper guide plate on said carrier arranged to shift with said platen and hold paper close to the printing line, and a finger on said plate extending across the printing line to hold said paper.
20. In a typewriting machine, the combination with a traveling platen, of a pair of paper guiding scale plates pressing lightly against said platen, points extending upward from said plates to cover the printing line, one of said plates extending each side the printing point, the points aforesaid being so spaced as to keep clear the printing point.
21. In a typewriting machine, the combination with a traveling platen, of a pair of paper guiding plates pressing lightly against said platen, said plates extending over a tensionally operative horizontal range, each side the printing point, each having at intervals points projecting up over the printing line, said points being in contact with the paper and adapted to hold it stretched over the printing point.
22. In a typewriting machine, the combination with a traveling platen, of a pair of paper-guiding scale plates pressing lightly against said platen and extending over a tensionally operative horizontal range, one upon each side of the printing point, each having a point adjacent the printing point projecting up to cover the printing line, and another point spaced more than a letter-space from said point similarly covering said line; said points arranged to leave the letters on said line open to be read and the space above said points being completely free of anything to interfere with seeing the matter which has been written.
23. A ribbon carrier comprising a split lower portion, a split upper portion, wings extending laterally from said upper portion, and points extending from said wings to cover the printing line; said points being spaced so as not to interfere with the reading of letters written on said line, and the space above said points being free of anything to interfere with seeing the matter which has been written.
24. In a typewriting machine, the combination with a vibrating ribbon-carrier normally below the printing line, of a scale on said carrier adjacent said line adapted to indicate letter-spaces on said written line.
25. In a typewriting machine, the combination with a vibrating ribbon-carrier normally resting below the ribbon line, of a scale on said carrier adjacent said written line, and resilient points spaced at intervals rising upwardly from said scale above the printing line.

In testimony that I claim the foregoing as my own, I have hereto affixed my signature in the presence of two witnesses.

GEORGE SELDEN WATTS.
